UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

DRAFT-RIGGING BACKSTOP.

Application filed October 21, 1921. Serial No. 509,346.

To all whom it may concern:

Be it known that I, DONALD S. BARROWS, a citizen of the United States, residing at Rochester, in the county of Monroe and State of New York, have invented certain new and useful Improvements in Draft-Rigging Backstops; and I do hereby declare the following to be a full, clear, and exact description of the invention, such as will enable others skilled in the art to which it appertains to make and use the same.

My invention relates to draft rigging backstops which are secured to spaced sills of a railway car to afford means for transmitting to the car underframe the buffing shocks to which the draft rigging mechanism is subjected when in service.

The principal object of the invention is to provide a backstop of great strength which may be securely attached to the car sills with a minimum expenditure of labor, which is comparatively light in weight, and in which the liability of the occurrence of manufacturing defects is reduced.

Generally stated, the principal feature of the invention resides in constructing a backstop with side walls which are united at their forward ends by an end wall forming an abutment for a movable part of the draft rigging, and in uniting said end wall to the side walls by rearwardly extending upwardly divergent webs.

A further feature of the invention consists in forming the backstop with side walls which are united by a forward end wall adapted to constitute an abutment for a movable part of the draft rigging, and in connecting the said end and side walls by longitudinally extending upwardly divergent webs which themselves are united to upwardly extending webs or flanges integrally connected to the said end wall.

Another feature of the invention consists in providing a backstop with side walls, a forward end wall united to said side walls, and a centrally disposed horizontally extending hollow column connected to said end wall and extending rearwardly therefrom.

Other features of the invention residing in particular details of construction and characteristic relations of structural parts will hereinafter appear.

In the drawings illustrating the invention

the scope whereof will be pointed out in the claims,

Figure 1 is a plan view of a backstop embodying the invention showing its assembled relation to a portion of the underframing of a car and to the rear end of a draft rigging mechanism.

Figure 2 is a horizontal section of the construction shown in Fig. 1, the view being taken on the line 2—2, Fig. 4, and the draft rigging being in plan.

Figure 3 is a sectional view on the line 3—3, Fig. 1, the draft rigging being omitted.

Figure 4 is a transverse section on the line 4—4, Fig. 3.

Figure 5 is a rear end elevation of the construction shown in Fig. 1.

Figure 6 is a plan view of a modified form of backstop embodying the invention.

Figure 7 is a vertical sectional view of the construction shown in Fig. 6, taken at one side of the central vertical web.

Figure 8 is a transverse section on the line 8—8, Fig. 7.

Figure 9 is a rear elevation of the modified form of backstop shown in Figs. 6, 7 and 8.

Figure 10 is a detail plan view of a modified form of construction which may be employed for the forward end of the backstop.

Figure 11 is a sectional view on the line 11—11, Fig. 10.

The backstop is secured between the spaced center sills 1 of the car underframe. The sills illustrated are of a well known composite form, but it is to be understood that any other form of sills may be employed if desired. The draft rigging mechanism illustrated in the drawings and generally designated by the reference numeral 2, is of the well known type involving a horizontal yoke 3 and a rear follower 4, but this particular draft rigging is intended to serve merely as an illustration and is not disclosed with the intention of limiting the invention to use in conjunction therewith.

The backstop is provided with parallel side walls 5 which are adapted to be secured to the respectively adjacent sills 1 of the car, the attachment being preferably made by rivets 6 that may be arranged in three vertically spaced rows extending longitudinally of the backstop.

At its forward end the backstop is provided with a vertical end wall 7 which in-

tegrally unites the side walls 5 and is adapted to form an abutment for a movable part of the draft rigging, said movable part in the case illustrated in the drawings being the draft yoke 3. Projecting rearwardly from the forward end wall 7 longitudinally of the backstop are upwardly divergent inclined webs 8 which preferably are united along the center line of the backstop and 10 may be upwardly curved so as to afford increased space facilitating the driving of the middle row of rivets 6 at the forward end of the structure. The forward end wall 7 and the upwardly divergent inclined webs 15 may also be integrally united by webs 9 which extend upwardly from said webs 8 and may converge toward the upper part of the backstop and be of curved form if desired, the said webs 8 and 9 constituting in 20 effect a centrally disposed horizontally extending hollow column for receiving longitudinal thrusts delivered to the end wall 7. To afford further strength for resisting longitudinal forces, the backstop may also 25 be provided with a longitudinally extending vertical web 10 which is united to the end wall 7, passes between the upwardly divergent webs 8 and is connected to the latter along their junction line.

30 It is preferred to form the backstop with transverse webs 11 extending inwardly from the side walls 5 toward the king bolt opening 12 with which devices of this character are customarily provided. These transverse webs 11 are united to the transversely inclined webs 8 and 9 as well as to the vertical longitudinal web 10. A transversely extending horizontal web 13, which is united to the webs 11 and to the vertical longitudinal 35 web 10, may also be advantageously employed for transversely connecting the side walls 5 of the backstop.

The rear portion of the backstop may be conveniently provided intermediate of its height with a plurality of spaced horizontal webs 14 disposed upon opposite sides of the central row of rivets 6 in horizontal alignment with the forward end wall 7 and the webs 8 and 9 forming the hollow column by 40 which said end wall is braced. These horizontal webs 14 extend between and connect the side walls 5 of the casting. The side walls are also preferably connected along the lower edges at their rear ends by a horizontally extending web 15 which is united to a centrally disposed vertical flange 16 connecting the webs 14 to the transversely extending webs 11. The lower horizontal web 15, as shown, may extend forwardly so as to 45 unite with the vertical longitudinal web 10 and form a transverse connection for the side walls 5 somewhat in advance of the king bolt opening 12.

In the modified embodiment of the invention illustrated in Figs. 6 to 9, inclusive, the

side walls 17 of the backstop are united by a forward end wall 18 which, like the end wall 7, is adapted to form an abutment for a movable part of the draft rigging. As in the case of the construction heretofore described, the side walls 17 and end wall 18 are integrally united by upwardly divergent, preferably curved, webs 19 which extend rearwardly from said end wall to the transversely extending vertical webs 20 projecting inwardly from the side walls toward the king bolt opening 21. The upwardly extending webs 22 united to the end wall 18 and to the said divergent webs 19 in this instance do not converge upwardly, as do the corresponding webs 9 embodied in the form of my invention illustrated in the principal figures of the drawing, but are disposed in longitudinally extending vertical planes. They may be connected at their rear ends to 85 the transverse webs 20 and to the horizontal web 23 tying the upper edges of the side walls 17 together adjacent the king bolt opening.

The modified form of the front end of the backstop illustrated in Figs. 10 and 11 involves side walls 24 adapted to be received between the sills of the car and an end wall 25 for engaging a movable part of the draft rigging. The side walls 24 and the end wall 25 are integrally united by longitudinally extending upwardly divergent webs 26 and the latter are also united to the said end wall by upwardly convergent webs 27, the webs 26 and 27 preferably being of curved form and constituting a longitudinally extending centrally disposed hollow column the upper and lower walls of which are respectively united in a vertical plane passing through the longitudinal axis of the backstop.

A backstop constructed in accordance with my invention enables the metal to be disposed in a manner imparting to the structure great strength per unit of weight.

I claim:

1. A draft rigging backstop comprising side walls adapted to be secured to spaced car sills, a forward end wall united to said side walls and adapted to form an abutment for a movable part of the draft rigging, and rearwardly extending upwardly divergent webs uniting the forward end wall to said side walls.
2. A draft rigging backstop comprising side walls adapted to be secured to spaced car sills, a forward end wall united to said side walls and adapted to form an abutment for a movable part of the draft rigging, and longitudinally extending upwardly divergent webs uniting said forward end wall to said side walls.
3. A draft rigging backstop comprising side walls adapted to be secured to spaced car sills, a forward end wall united to said side walls,

- side walls and adapted to form an abutment for a movable part of the draft rigging, and longitudinally disposed divergent inclined webs extending on opposite sides of the longitudinal axis of the backstop and uniting said forward end wall to said side walls at points intermediate the edges thereof.
4. A draft rigging backstop comprising side walls adapted to be secured to spaced car sills, a forward end wall uniting said side walls and adapted to form an abutment for a movable part of the draft rigging, and a centrally disposed horizontally extending hollow column connected to said forward end wall and extending rearwardly therefrom.
5. A draft rigging backstop comprising side walls adapted to be secured to spaced car sills, a forward end wall uniting said side walls and adapted to form an abutment for a movable part of the draft rigging, and vertically curved webs uniting said forward end wall to said side walls at points intermediate the edges thereof.
6. A draft rigging backstop comprising side walls adapted to be secured to spaced car sills, a forward end wall uniting said side walls and adapted to form an abutment for a movable part of the draft rigging, and longitudinally extending transversely upwardly inclined webs united to said forward end wall and extending rearwardly therefrom.
7. A draft rigging backstop comprising side walls adapted to be secured to spaced car sills, a forward end wall uniting said side walls and adapted to form an abutment for a movable part of the draft rigging, a king bolt opening, transverse webs respectively united to said side walls and extending toward said king bolt opening, and upwardly inclined webs uniting said forward end wall to said side walls and transverse webs.
8. A draft rigging backstop comprising side walls adapted to be secured to spaced car sills, a forward end wall uniting said side walls and adapted to form an abutment for a movable part of the draft rigging, longitudinally extending upwardly divergent webs united to said forward end wall and to said side walls adjacent said end wall, and upwardly extending webs united to said end wall and to said divergent webs.
9. A draft rigging backstop comprising side walls adapted to be secured to spaced car sills, a forward end wall uniting said side walls and adapted to form an abutment for a movable part of the draft rigging, longitudinally extending upwardly divergent webs united to said forward end wall and to said side walls, and upwardly convergent webs united to said end wall and to said divergent webs.
10. A draft rigging backstop comprising side walls adapted to be secured to spaced car sills, a forward end wall uniting said side walls and adapted to form an abutment for a movable part of the draft rigging, upwardly divergent webs uniting said end wall and said side walls, and a longitudinally extending vertical web united to said forward end wall and extending rearwardly therefrom between said divergent webs.
11. A draft rigging backstop comprising side walls adapted to be secured to spaced car sills, a forward end wall uniting said side walls and adapted to form an abutment for a movable part of the draft rigging, longitudinally extending upwardly divergent webs united to said forward end wall and to said side walls, upwardly convergent webs united to said end wall and to said divergent webs, and a longitudinally extending web united to said end wall and projecting into the space between said convergent webs and said divergent webs.
12. A draft rigging backstop comprising side walls adapted to be secured to spaced car sills, a forward end wall uniting said side walls and adapted to form an abutment for a movable part of the draft rigging, a plurality of horizontally disposed spaced webs connecting said side walls, a vertical web in the longitudinal axis of the backstop, webs extending inwardly from said side walls toward said vertical web and united to said spaced webs and side walls, and inclined webs united to said forward end wall, said side walls and said inwardly extending webs.
13. A draft rigging backstop comprising side walls adapted to be secured to spaced car sills, a forward end wall united to said side walls and adapted to form an abutment for a movable part of the draft rigging, a centrally disposed hollow column united at its forward end to said end wall and extending rearwardly therefrom, said column being open interiorly from end to end, and webs uniting said column to said side walls.

In testimony whereof I affix my signature.

DONALD S. BARROWS.
